US00D501385S

(12) **United States Design Patent**
Cheung et al.

(10) Patent No.: **US D501,385 S**
(45) Date of Patent: **** Feb. 1, 2005**

(54) **DRILL**

(75) Inventors: **Benson Chun Kit Cheung**, Kowloon (HK); **Daniel Alex Chunn**, Kowloon (HK); **Frank Lenz**, Berlin (DE)

(73) Assignee: **One World Technologies Limited**, Hamilton (BM)

(**) Term: **14 Years**

(21) Appl. No.: **29/204,232**

(22) Filed: **Apr. 27, 2004**

(51) LOC (7) Cl. **08-01**

(52) U.S. Cl. **D8/68**

(58) Field of Search .... D8/14.1, 61, 62, D8/63, 64, 65, 66, 67, 68, 69, 70; 81/57.11, 429, 464, 465, 466, 469, 489; 173/13, 169, 178, 213, 217; 227/8, 114, 120, 130, 136, 142; 310/50; 408/20, 124, 125, 234, 241 R; 451/358

(57) **CLAIM**

The ornamental design for a drill, as shown and described.

DESCRIPTION

FIG. 1 is a top perspective view of a first embodiment of a drill of the present invention;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a rear view thereof;

FIG. 8 is a top perspective view of a second embodiment of a drill of the present invention;

FIG. 9 is a first side view thereof;

FIG. 10 is a second side view thereof;

FIG. 11 is a top view thereof;

FIG. 12 is a bottom view thereof;

FIG. 13 is a front view thereof;

FIG. 14 is a rear view thereof;

FIG. 15 is a top perspective view of a third embodiment of a drill of the present invention;

FIG. 16 is a first side view thereof;

FIG. 17 is a second side view thereof;

FIG. 18 is a top view thereof;

FIG. 19 is a bottom view thereof;

FIG. 20 is a front view thereof; and,

FIG. 21 is a rear view thereof.

The ornamental design which is claimed is shown in solid lines in the drawings. Any broken lines in the drawings are for illustrative purposes only and form no part of the claimed design.
